UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,188,835.

Specification of Letters Patent. Patented June 27, 1916.

Application filed December 31, 1913. Serial No. 809,595.

To all whom it may concern:

Be it known that I, LYMAN R. ROBERTS, a citizen of the United States, residing in Rutherford, in the county of Bergen and 5 State of New Jersey, have invented certain new and useful Improvements in Type-Writing Machines, of which the following is a specification.

My invention relates to an improved form 10 of type-bar action for typewriting machines. The invention is shown as applied to a machine of the front-strike type, in which the type-bars are normally horizontally disposed and movable about pivots upwardly 15 and rearwardly to strike against the front face of the platen. The type-bars are actuated by horizontally disposed thrust rods or links, each pivotally connected at one end to a type-bar, and at its other end supported 20 and guided, as by means of a pivoted link. Key levers beneath the type-bars are connected by upwardly extending links to the thrust rods, whereby, when a key is depressed, the thrust rod is actuated to im- 25 part a printing stroke to the type-bar.

The point at which the thrust bar is connected to the type-bar is so located that the pull of the link connecting the key lever to said thrust bar is substantially in the direction 30 of movement of said pivot point, whereby, when the key is depressed, the initial movement of the type-bar is comparatively slow, but during the type stroke the direction of movement of the thrust bar gradually changes to effect a comparatively rapid movement of the type-bar, thereby absorbing the momentum or power applied to the key and effecting a powerful type stroke.

The movement of the thrust bars or links 40 may be limited by adjustable stops set to engage the thrust bars just before the types strike the platen and thus positively limit the pivotal movement of the type-bar, the resiliency of the type-bars permitting the 45 types to be carried by momentum to the printing point.

Other features and advantages will hereinafter appear.

In the accompanying drawings, Figure 1 50 is a part sectional front elevation of a type-writing machine with the present invention applied thereto. Fig. 2 is a detail view showing the method of mounting the bearing blocks. Fig. 3 is a transverse sectional ele- 55 vation taken near the center of the machine,

showing in full lines a key depressed and the type-bar thrown up, and showing in dotted lines the type-bar and key in normal position. Fig. 4 is a similar view taken near the left-hand side of the machine and 60 showing in full lines a type-bar and key in normal position. Fig. 5 is a perspective view of a bearing block.

Key-levers 1, which are pivotally mounted on the transverse shaft or bridge 2, supported in the machine frame are each pivotally connected by an upwardly and rearwardly extending connecting link 3, to a thrust bar or link 4 forming an actuator for a type-bar, and which is supported and 65 guided at one end by a normally upstanding arm or link 5, and at its other end is pivoted at 6 to a downwardly projecting arm 7 of a type-bar 8. The type-bars 8 are mounted in suitable bearings 12 on plate-like hangers 13, which are secured in, and project downwardly from, the radial slots of the segment 9, the latter being fixed to the machine frame.

The type-bars 8 are normally in a substantially horizontal position supported in a basket 8' and are adapted to swing upwardly and rearwardly to bring the types 10 thereon to the printing point on the front face of the platen 11. This movement of 85 the type-bar, when a key is depressed, may be considered as due to the resultant of two forces produced by the power applied through the link 3. The first of these forces is due to the swinging movement of 90 the thrust rod 4 about the pivot 5^a which connects the rod 4 to the link 5, and at the commencement of the type stroke is approximately in the direction of movement 95 of the pivot 6 connecting said thrust rod 4 to the type-bar. The speed of the type-bar relatively to that of the key is comparatively slow at the start, but as the type-bar moves upward and the pivot 6 is carried about the type-bar pivot 12^a as a center, the direction 100 of movement of said pivot 6 gradually changes, and near the completion of the type stroke is approximately perpendicular to the line of pull of the link 3, so that the movement of the type-bar relatively to the 105 key is comparatively rapid. The second force acting through the rod 4 is a forward thrust imparted to the rod at the pivot point 5^a due to the downward pull of the link 3 on the rod 4 reacting at the pivot 110

110

point 5^a. It will be noted that this thrust is most effective during the final upward movement of the type-bar.

The thrust rod or member 4 at the first 5 part of the stroke operates substantially as a floating lever, having a floating fulcrum 5^a. The lever is of the third order, power being applied thereto between its ends by link 3, and the work being done at point 6, 10 where the lever is pivoted to the short arm 7 of the type-bar.

At the initial portion of the down stroke, the resistance of the key is very light, this being due partly to the fact that the key- 15 driven link 3, is connected to the lever 4 near the end 6 thereof which drives the type-bar, and also partly to the fact that said link 3 normally pulls not only downwardly but forwardly and hence acts more 20 effectively on the swinging arm 7 of the type bar.

During the printing stroke of the type-bar, the members 4 and 5 operate in the manner of a toggle, being driven by the 25 link 3, which finally straightens out the toggle. During the last portion of the movement of the toggle, the speed of the type-bar is accelerated in proportion to the speed of the key; there being but little downward 30 movement of the link 3 during the last half or more of the down stroke of the members 4 and 5, which effects the last third of the printing stroke of the type-bar 8. Thus the 35 resistance of the key to the finger type is relatively light at the beginning of the stroke, and the resistance gradually increases, so that the momentum of the operator's hand is absorbed, and the hand is gradually brought to rest, while the type-bar 40 is caused to strike smartly on the platen.

The purchase of the floating lever 4 on the short arm 7 of the type-bar diminishes from the beginning of the stroke, and disappears when the pivot 6 is about directly 45 beneath the type-bar pivot 12; the completion of the stroke of the type-bar being due to the toggle-closing action of the parts 4, 5, whereby 4 is thrust endwise in the direction in which the point 6 is moving at this time; 50 the part 4 therefore first acting as a lever and then as a link or thrust rod.

At Fig. 4 the same remarks apply, but it will be seen that the link 3 is still more inclined to the rear, so as to improve the touch 55 of the key and the stroke of the type-bar. It will also be understood that all of the links 3 may have about the same rearward inclination as at Fig. 4, thus increasing the thrusting action of the parts 4 and improving 60 the operation of the mechanism.

Each link 5 is pivoted on a pin 14 and has a rearwardly extending arm 15 connected through a returning spring 16 to the key lever 1. The pivot pins 14 are mounted in 65 bearing blocks 17, Fig. 4, each of which is

bifurcated or formed with a slot 18 to receive the link 5, and has a reduced end or shank 19 adapted to be clamped between a pair of supporting bars 20 connected to the machine frame. Clamping screws 21, as 70 shown in Figs. 2 and 3, may be interposed between the shanks 19, said screws extending freely through one bar 20 and threaded into the other for clamping the bearing blocks in position. 75

The supporting bars 20 are concentric with the segment 9, so that all of the thrust rods 4 will extend in a substantially horizontal direction. A stop rod 22 located forward of the supporting bars 20 and parallel therewith, is provided with adjustable stops, shown as screws 23, threaded through the rod 22 in position to engage the bars 4 and thereby determine their limit of movement. These stops are so adjusted that they will be engaged by said links when the types are a short distance from the platen and thus positively limit the rotation of the type-bars about their pivots, the resiliency of the type-bars permitting the types to complete 90 their movement to the platen. The length of the links 4 and 5 may be such that they are brought into a straight line and stop the pivotal movement of the type-bar when the types are a short distance from the platen, 95 allowing the types to spring to the printing point.

As indicated in Fig. 1, the type-bars, except those located at the center, are in planes inclined to a vertical plane, the extent of 100 inclination being proportional to the distance of the type-bars from the center of the segment. The forward ends of the thrust rods 4 are provided with downwardly curved sections 24 to accommodate the 105 shanks of the type-bars, and said sections 24 are also twisted through an angle corresponding to the inclination of the respective type-bars as indicated in Fig. 1, to bring the ends of the links parallel with the 110 type-bars and thus prevent them from binding.

The weight of the type-bars may be substantially balanced by the weight of the key levers and other moving parts, as the weight 115 of the key levers acting through the links 3 tends to swing the type-bars upward. As the turning moment applied to the type-bar by the pull on the link 3 and tending to swing the type-bar upward, decreases during the type stroke, and as the turning moment due to the weight of the type-bar and tending to swing the type-bar downward, also decreases during the type-stroke, the counter-balancing action of the key levers 120 on the type-bars is effective in all positions. In other words, with the spring 16 disconnected, the type-bar and key have a counter-balancing action on each other in any position. This simplifies the problem of pro- 125

viding suitable returning springs for the type actions, and also renders the action more desirable in many cases.

Variations may be resorted to within the scope of the invention, and portions of the improvements may be used without others.

Having thus described my invention, I claim:

1. In a type-bar action for typewriting machines, the combination with a type-bar and a type-key, of a thrust bar pivoted to the type-bar, a link connecting the key lever and thrust bar, and transmitting an operating force from the key lever to the thrust bar in the direction of length of the link, and means to guide the thrust bar for movement bodily in a direction transverse to that of the link.

2. In a typewriting machine, the combination with a type-bar, of a key-lever, an actuating thrust bar pivoted to the type-bar and extending rearwardly therefrom substantially parallel with the key lever, and a link connecting the key lever and said thrust bar, and free to transmit an operating force in the direction of its length directly from the key lever to the thrust bar for actuating the type-bar.

3. In a typewriting machine, the combination with a horizontally disposed type-bar and a key lever, of a thrust bar pivoted to the type-bar and extending substantially parallel with the key lever, a second pivot for the thrust bar, and a link connecting the key lever and thrust bar and transmitting an operating force to the thrust bar comprising a combined endwise thrust of the bar and a turning moment of the bar about said second pivot as a fulcrum.

4. In a front-strike writing machine, the combination of a type-bar pivoted to swing upwardly and rearwardly to the printing point, a thrust bar connected to the type-bar below and in rear of the type-bar pivot and extending rearwardly from the type-bar, a key lever, a link connecting the key lever to the thrust bar and transmitting an operating force in the direction of its length to the thrust bar, and means for supporting and guiding the thrust bar, and causing said force to produce a combined downward pull and forward thrust of the thrust bar on the type-bar.

5. The combination with a pivoted type-bar, of an actuating bar pivoted thereto to move, at its point of connection with the type-bar, about the type-bar pivot as a center, a link pivoted to said bar and substantially perpendicular thereto when the type-bar is in its normal position of rest, a key lever, and a connection between the key lever and said bar to operate the latter to a position in which the said bar and link are substantially in line and the type-bar adjacent the printing position.

6. In a typewriting machine, the combination with a platen, of a pivoted type-bar, a thrust bar pivoted to the type-bar to swing in an arc about the type-bar pivot as a center during the type stroke, a link pivoted to the thrust bar and having an angular relation thereto, a key lever, and a connection between the key lever and said bar for swinging the said bar and link into a substantially straight-line position with the type-bar near the printing point.

7. In a typewriting machine, the combination with a platen, of a pivoted type-bar, a thrust bar pivoted to the type-bar to swing in an arc about the type-bar pivot as a center during the type stroke, a link pivoted to the thrust bar and having an angular relation thereto, a key lever, a connection between the key lever and said bar for swinging the said bar and link into a substantially straight-line position with the type-bar near the printing point, and an adjustable stop to engage the thrust bar when in such position.

8. The combination with a type-bar swinging rearwardly to the printing point, of a key lever, a thrust rod pivoted to the type-bar and extending rearwardly therefrom, a link connecting the key lever and said rod and arranged to exert a direct pull on the rod in the direction in which the link extends, the pivot point of said rod and type-bar being so positioned that the pull of the link during the initial movement of the type-bar is in a direction substantially parallel with the direction of movement of said pivot, the direction of movement of the pivot relatively to the pull of the link gradually changing during the type stroke to a direction approximately perpendicular to said pull, and means for supporting and guiding the rod for bodily movement as the type-bar swings, and causing the pull of the link to produce an endwise forward thrust of said rod on the type-bar during the final portion of the type stroke.

9. The combination with a pivoted type-bar, of a floating bar pivoted at one end to the type-bar to swing the type-bar about its pivot from its position of rest toward printing position, a link to which the other end of said floating bar is pivoted, a key lever, and a link connecting said lever to said floating bar at a point intermediate the ends of the floating bar and a substantial distance from said first-mentioned link, said floating bar operating during a portion of the type stroke as a lever fulcrummed to said first-mentioned link and having mainly a swinging movement about its point of connection with said first-mentioned link as a fulcrum.

10. In a typewriting machine, the combination with a pivoted type-bar and a key lever, of a pivotally-mounted arm, a thrust bar connecting said arm to the type-bar,

- 46 said arm and thrust bar being substantially perpendicular to each other when the type-bar is in its normal position of rest and movable during the type stroke to a position in 5 which the thrust bar and arm are in a substantially straight line, and a connecting link between the key lever and said thrust bar for transmitting an operating force from the key lever to actuate the thrust bar, 10 said connecting link normally supporting the weight of the key lever and applying a counter-balancing force to the type-bar.
- 47 11. In a typewriting machine, the combination with a pivoted type-bar and a key lever, of actuating means for the type-bar comprising a thrust bar pivoted to the type-bar, a pivotally-mounted arm pivoted to said thrust bar and extending substantially at right angles thereto when the type-bar is in 15 its normal position of rest, and a link connecting the key lever to said thrust bar for transmitting an operating force from the key lever to the thrust bar, the latter having mainly a swinging movement about its 20 point of connection with said arm during the initial portion of the type stroke, the movement of said thrust bar gradually changing from said swinging movement to a bodily endwise movement or thrust applied 25 to the type-bar as the latter nears the printing point and the said thrust bar and the swinging arm move toward a straight-line position, the weight of the key lever being supported by said connecting link, and 30 transmitting through the link a counter-balancing force applied to the type-bar and effective for substantially all positions of 35 the type-bar.
- 48 12. In a typewriting machine, the combination with a pivoted type-bar and a key lever, of a thrust bar pivoted at one end to the type-bar, a swinging arm to which the other end of the thrust bar is pivoted, and a link connecting the key lever to said thrust 40 bar and supporting the weight of the key lever, said weight operative through said thrust bar to apply a counter-balancing force to the type-bar, said thrust bar arranged to have mainly a swinging movement about its point of connection with said swinging arm during the initial portion of the type stroke, the movement of said thrust bar gradually changing to mainly an endwise bodily movement or thrust applied to 45 the type-bar as the latter approaches the printing point, said thrust bar and swinging arm being substantially perpendicular at the beginning of a type stroke and moving toward a straight-line position during the 50 type stroke.
- 49 13. The combination with a pivoted type-bar and a key lever, of a thrust bar pivoted at one end to the type-bar, a swinging arm to which the other end of the thrust bar is 55 connected, said arm extending substantially 60 at right angles to the thrust bar while the type-bar is in its normal position of rest, a link connecting the key lever to the thrust bar and applying an operating force to the thrust bar, causing the latter to swing about its point of connection with said arm during the initial part of the type stroke, said force operable to swing the thrust bar and swinging arm toward a straight-line position during the continued portion of the type stroke, and thereby cause the thrust bar to move longitudinally and apply an endwise thrust to the type-bar, and a stop to limit the movement of the thrust bar when substantially in line with said swinging arm and with the type-bar adjacent the printing point to permit the free end of the type-bar to spring forward to the printing point.
- 50 14. In a typewriting machine, the combination with a key lever and a pivoted type-bar, of a pivotally-mounted arm extending upward from its pivot, a thrust bar connected to said arm above its pivot, and connecting said arm to the type-bar, a connecting link between the key lever and the thrust bar for transmitting an operating force from the key lever to the thrust bar, and causing the latter to swing the type-bar, said thrust bar swinging said arm toward a position in alignment with the thrust bar, and a stop to limit the movement of the thrust bar and said arm when the key lever has completed its stroke, the body of the type-bar being brought to rest as the thrust bar engages said stop, and the type-carrying end of the type-bar being permitted to spring forward to the printing position.
- 51 15. In a typewriting machine, the combination with a key lever and a swinging type-bar, of a pivotally-mounted arm, a driving link connecting said arm to the type-bar, and connecting means transmitting a driving force from the key lever to said link for actuating said link and arm and causing the link to drive the type-bar, said link and arm being constructed to swing to a straight-line position at the conclusion of the driving stroke of said arm, thereby to bring the hub or body of the type-bar to rest, while permitting its type-carrying end to spring forward to the printing point.
- 52 16. In a typewriting machine, the combination with a key lever and a type-bar, of a pivoted arm, a thrust bar between said arm and the type-bar, and a connecting link from the key lever to said thrust bar for actuating the latter during the type stroke and swinging said thrust bar and arm toward a straight-line position, and bringing the hub of the type-bar to rest at the completion of the key stroke in position to permit the type-carrying end of the type-bar to spring forward to the printing point.
- 53 17. In a type action for typewriting ma- 130

chines, the combination with a type-bar arranged to swing from a recumbent position to an upright position at the printing point, of a pivoted arm extending upwardly from its pivot, a thrust bar connected to said arm above said pivot and extending forwardly therefrom and pivoted to the type-bar, a key lever beneath the type-bar, and a link connecting the key lever with said thrust bar, the point of connection between the thrust bar and type-bar being such that during the initial downward movement of the

key lever, the thrust bar swings downwardly about its point of connection with said arm, and during the continued movement of the type-bar has a forward endwise movement or thrust in a forward direction to the type-bar, whereby the thrust bar and said swinging arm are moved toward a straight-line position during the type stroke.

LYMAN R. ROBERTS.
